(57) **CLAIM**

The ornamental design for a golf cart cover, as shown and described.

DESCRIPTION

FIG. 1 is a front view of a golf cart cover, showing my new design;

FIG. 2 is a rear view thereof;

FIG. 3 is a left side view thereof;

FIG. 4 is a right side view thereof;

FIG. 5 is a bottom plan view thereof;

FIG. 6 is a top plan view thereof;

FIG. 7 is a use state view thereof;

FIG. 8 is a front and left side perspective use state view thereof; and,

FIG. 9 is a front and left side perspective view thereof.

The dot-dash broken lines shown in the drawings illustrate portions of the golf cart cover that form no part of the claimed design.

The dashed broken lines found along the perimeter trim are stitching that forms a part of the claimed design.
